UNITED STATES PATENT OFFICE.

LOUIS GOLD, OF CHICAGO, ILLINOIS.

DESIGN FOR A LAMP SHADE.

Application filed April 11, 1927. Serial No. 21,547. Term of patent 3½ years.

To all whom it may concern:

Be it known that I, LOUIS GOLD, a citizen of the United States, residing at Chicago, in the county of Cook and State of Illinois, have invented a new, original, and ornamental Design for a Lamp Shade, of which the following is a specification, reference being had to the accompanying drawing, in which a perspective view of the design is shown.

I claim:—

The ornamental design for a lamp shade, as shown.

In testimony whereof I affix my signature.

LOUIS GOLD.
